UNITED STATES PATENT OFFICE.

WILLIAM A. DOBSON, OF BRIDGEPORT, CONNECTICUT.

DESIGN FOR A CURLING-IRON HOLDER.

SPECIFICATION forming part of Design No. 25,316, dated March 31, 1896.

Application filed February 5, 1896. Serial No. 578,168. Term of patent 7 years.

To all whom it may concern:

Be it known that I, WILLIAM A. DOBSON, a citizen of the United States, residing at Bridgeport, in the county of Fairfield and State of Connecticut, have invented and produced a new and original Design for Lamp-Chimney Holders for Heating Curling-Irons; and I do hereby declare the following to be a full, clear, and exact description of the same, reference being had to the accompanying drawing, forming a part thereof.

The figure is a perspective of a curling-iron holder embodying my novel design.

The leading feature of my design consists in a flat metallic plate having curved and straight edges substantially as shown and a plurality of different-sized openings and legs or projections extending downward and inward and outward from the edge thereof.

A is a flat metallic plate having an elongated opening 1, a smaller elongated opening 2, and a series of small circular openings 3, arranged in a circle around the openings 1 and 2. The legs project downwardly from the edge of the plate A, as at 4, then bend inwardly, as at 5, and finally bend downwardly and are curved, as at 6.

What I claim is—

The design for a curling-iron holder, substantially as shown and described. 30

In testimony whereof I affix my signature in presence of two witnesses.

WILLIAM A. DOBSON.

Witnesses:

A. M. WOOSTER,
S. V. RICHARDSON.
